UNITED STATES PATENT OFFICE.

JESSE D. LASSWELL, OF CHICAGO, ILLINOIS.

CUTTER.

Application filed October 7, 1926. Serial No. 140,145.

This invention relates to printers' lead and rule cutters and trimmers and represents an improvement over United States Patent No. 650,193 issued to H. B. Rouse
5 May 22, 1900.

The various printers' lead and rule cutters with which I am familiar are adapted solely for cutting the work in a transverse direction into desired lengths. It is a well known fact to those skilled in the printing art that in instances where the last line of a linotype slug contains but a few words, the adjacent blank space will come into contact with the inking rolls and transmit a black mark to the printed page. To overcome this it is necessary to cut down, at least to quad height, the stock of the slug at the site of a blank space at the end of the last type line. It is therefore the primary object of my invention to provide a machine of this character which in addition to serving as a transverse slug or rule cutter, is also adapted to cut longitudinally of a linotype slug and to trim down to quad or other desired height 25 the typeless portions to prevent the inking devices from coming into contact therewith and consequently smearing the printing.

In its more limited aspects the invention contemplates a machine of the kind stated, 30 having a novel longitudinally extending gage strip and mounting and holding means therefor whereby the linotype slug or other work may be accurately positioned either transversely or longitudinally with respect 35 to the plane of the cutting elements.

The invention also has for an object to furnish in a machine as characterized, an improved form of coacting cutters which admit of the accurate severance of a rectangular ended longitudinal section from a linotype slug or other work at any point throughout its length, and without detracting from the utility of the cutters when used for transversely cutting work.

40 A further object of the invention is the provision of a peculiar relative arrangement of cutters, mounting and operating elements therefor whereby the linotype slugs or other work may be freely moved in the direction 45 of their lengths transversely of the machine without obstruction, the entire transverse portion of the machine in the vicinity of the cutters, at one side thereof being clear so that the operator can readily and accurately 50 determine just the right depth and starting point of a longitudinal cut to reduce a type-

less portion of a slug to quad height, it being understood that such arrangement admits of the ready manipulation of gage or 55 guide elements for the slug.

Other objects and advantages will be apparent during the course of the following description.

In the accompanying drawings forming a part of this application and in which like numerals are employed to designate like parts throughout the same,

Figure 1 is a perspective of the improved machine;

Figure 2 is a group perspective of a medial adjustable rib and the means to hold the same in place;

Figure 3 is a vertical transverse sectional view taken on line 3—3 of Figure 1;

Figure 4 is a perspective of a fixed blade 75 embodied in the invention;

Figure 5 is an end view of the machine;

Figure 6 is a detail view illustrating a spring by which the movable blade is urged to elevated position;

Figure 7 is a group perspective illustrating a stop member embodied in the invention;

Figure 8 is a group perspective of an adjustable stop and the attaching means therefor;

Figure 9 is a detail sectional view taken on line 9—9 of Figure 10;

Figure 10 is a vertical longitudinal sectional view through the machine.

Figure 11 is a perspective view of a slug cut to quad height and showing the cut off part.

In the drawing wherein for the purpose of illustration is shown a preferred embodiment of the invention, the numeral 5 designates a bed having legs 6 by means of which the machine may be secured to a bench or other support.

In carrying out the invention, a bracket 100 7 is formed integral with the bed or is otherwise connected thereto and has connection with a hand lever 8 by means of which a knife blade 10 on a knife arm 11 may be forced downwardly into cutting engagement 105 with a slug. The blade 10 cooperates with a fixed blade 12 one of the functions of which is to cut the slugs transversely into the required lengths for setting up preparatory to printing.

The two blades 10 and 12 effectively cooperate in the transverse cutting of the slug

and in addition cooperate when it is desired to trim the slug longitudinally. More specifically, the last line of a paragraph may include only one or two words so that the remainder of the line is left blank. If the remaining part of the line or more specifically that part of the line which bears no type is not trimmed to quad-height or substantially to that height, it will receive ink from the inking rollers with the result that a black mark will appear on the paper printed. However, in accordance with this invention a slug may be quickly, neatly and easily trimmed so that that part of the slug which bears no type will not have contact with the roller or rollers as the case may be.

In carrying out the invention the medial gauge strip 15 mounted on the bed is provided with a central longitudinal rib 16 which as clearly shown in Figure 3 extends through the bed and has connection with an attaching strip 17. The attaching strip 17 is connected to the rib 16 by screw bolts 18 or other suitable fastening devices. At this point it is noted that the fastening devices 18 are left loose enough to permit of the easy longitudinal movement of the medial gauge strip 15.

The medial gauge strip is adapted to assume two extreme positions, one of which is illustrated in Figure 1 wherein the same is moved readwardly to that position it is adapted to occupy when the slugs are being snipped longitudinally. The rib 16 operates in a slot as illustrated in Figure 3 and the ends of the rib may engage the slots to limit endwise movement of the medial strip.

When the machine is to be employed for longitudinally cutting a slug, the medial strip 15 is retracted to the position shown in Figure 1 to allow sufficient space for the slug to extend transversely of the bed in operative proximity to the blades 10 and 12. Particular attention is directed to the fact that when the medial gauge strip 15 is in its retracted position the forward end of the same is on a line with a guide lug 22 so that the medial guide strip and the lug cooperate in properly positioning the slug to be snipped longitudinally to cut a portion of the same to quad-height.

The attaching plate 17 is provided with a downwardly directed flange 30 having an aperture 31 adapted to receive the tapered or cone shaped head of a locking pin 33. The locking pin, or more specifically the head of the same is urged into locking engagement with the flange 30 by a spring 34. A suitable knob 36 is mounted on the outer end of the locking pin 33 and forms a means whereby the pin may be manually retracted when it is desired to move the medial strip back for use in longitudinally cutting a slug or slugs. When the gauge strip 15 is moved back the cone shaped head of the pin 33

will merely have frictional contact with the adjacent surface of the flange 30 and will not interfere with the easy return of the gauge strip to the retracted position shown in Figure 1.

Figure 4 illustrates that the fixed blade 12 is provided with a lateral branch 41 at one end thereof for use in the longitudinal snipping of the slug. More specifically, the lateral branch 41 is located beneath one end of the movable blade 10 and cooperates with the same in severing the end of the part of the slug to be cut away. Without this lateral branch 41 the end of the cut would be rough and ragged. However, the lateral branch 41 does not interfere with the use of the machine in making transverse cuts as the movable blade 10 may extend entirely through the slug.

The gauge head 50 has connection with a square gauge rod 51 movable through a fixed upstanding portion 53 at one end of the bed. Figure 10 illustrates that the head 54 of a spring actuated pin 55 is transversely serrated for engagement with similar serrations on the underside of the gauge rod so that the rod may be securely held in an adjusted position. Suitable means such as a vertical rib within the opening for the reception of the pin 55 may be employed to hold the head 54 against turning. This causes the serrations in the head 54 to remain in an operative position with respect to the serrations in the underside of the rod 51.

Referring now to Figure 8, it will be seen that the gauge head 50 is provided with side plates 62 which extend into longitudinal grooves 63 in the bed 5 to guide the gauge head and hold the operative face of the same at right angles to the line of the medial strip 15. Attention is directed to the fact that the rectangular formation of the rod 51 provides greater stability and ease of operation and adjustment.

Also the projection of the plates 62 in grooves 63 below the face of bed 5 prevent a thin lead or rule from slipping under the gauge head 50 when it is moved in the direction of the blades.

It is further to be noted on reference to Figures 1 and 8 that the plates 62 are each provided with duplicate slots 62^a through which the fastening screws 62^b are extended into the block 50. This construction admits of the adjustment of plates 62 to project from the front face of the block 50 to act as a gauge in the event that the face of the block becomes untrue.

Figures 7 and 10 illustrate a gage device consisting of a block 70 having a surface cross slot 70^a in its top. An arm 72, narrower in width than the slot 70^a, is positioned therein and has its extended ends provided with forwardly projecting points 71 adapted to be positioned to engage the ends of

slugs or rules when the same are to be snipped transversely. The rear wall of the slot 70^a is provided with a bearing through which freely extends a threaded stem 72^a 5 and knurled wheel threaded thereon and working in a cross recess 70^b in the block, provides a suitable vernier adjustment whereby the arm 72 may be moved transversely of its slot 70^a to secure a fine adjustment of 10 the points 71 with respect to the work. The recess 70^a is closed by a holding plate 73. Major adjustment of the block 70 on the square supporting rod 75 of the same is accomplished by releasing a spring actuated 15 holding pin 76 on the underside of the block. The holding pin 76 has a head provided with serrations adapted to engage the serrations in the underside of the rod 75 so that it is a simple matter to move the block 20 70 along the rod 75 to provide for major adjustment or if desired to entirely remove the same.

In carrying out the invention the blade carrying arm 11 may be urged to elevated 25 position by means of a coil spring 79 anchored to the arm and to the adjacent leg 6.

With reference to the foregoing description taken in connection with the accompanying drawing it will be seen that the 30 transverse snipping of the slugs is not in any way complicated or interfered with by the alteration and improvement which makes it possible to cut the slugs or portions of them to quad-height so that those portions of the slugs which do not bear type 35 will receive no ink from the inking roller. When it is desired to cut slugs transversely it is only necessary to slide the medial gauge strip 15 to its advanced position with its forward end adjacent the stationary blade 12. Slugs are then laid alongside the strip with their rear ends backed by the gauge 40 block 50 and are snipped off as usual.

When it is desired to adjust the machine 45 to cut the slugs longitudinally, it is simply necessary to move the medial rib 15 back to a position where the forward end of the same is in line with the forward edge of the lug 22 so that these two surfaces cooperate in effectively holding the slug in position during the longitudinal cutting of the 50 same. As previously suggested the slug is cut longitudinally and transversely when it is desired to cut a portion of the slug to quad-height and thus the necessity for the lateral branch 41 on the fixed blade 40.

Referring to Figures 1 and 11, Figure 1 clearly illustrates in dotted lines a slug S disposed transversely of the machine and positioned with respect to the blades 10 and 12 so that a rectangular typeless section S¹ (Figure 11) will be snipped off from its front longitudinal portion adjacent the right hand end as seen in said figure. Thus the typeless edge of the slug S will be reduced 55

to quad height, leaving the extreme right hand type bearing end S² of the slug at its normal height.

It is also to be noted from Figure 1 that the blade 10 is mounted on an offset surface 70 11^a of the arm 11 so as to overhang the fixed blade 12 in spaced lateral relation to the plane of the major portion of the arm. Furthermore the bracket 7 and the bearing of arm 11 lie in a plane beyond or forwardly 75 of the plane of the offset end 41 of the stationary cutting blade 12. The advantage of this construction will be readily apparent to those skilled in the art. It enables the slug to have a clear unobstructed pathway 80 for transverse movement across the bed 5 of the machine, the ends of the slug projecting beyond the edges of the bed if necessary. By the same token, the clear unobstructed area mentioned combined with the offset 85 mounting of the blade 12 enables the operator to accurately set the slug S to just the proper relative position with respect to the knives so as to make sure not to cut away any of the type bearing portion of the slug. 90

Having thus described the invention, what is claimed is:

1. A machine for cutting slugs comprising a bed having a fixed knife, a movable knife cooperating with the fixed knife in cutting slugs, and a medial rib having means to position the slugs when extended longitudinally or transversely, one end of one of said knives having a lateral branch. 95

2. A machine for cutting slugs comprising a bed having a fixed knife, a movable knife cooperating with the fixed knife in cutting slugs, and a medial rib having means to position the slugs when extended longitudinally or transversely, said bed having means 100 cooperating with the forward end of said medial rib in positioning the slug when extended transversely of the machine, one end of one of said knives being provided with a lateral branch. 105

3. A slug cutting machine comprising a bed, a medial gauge strip movable on the bed and having a rib, an attaching plate connected to said rib, and a locking device to engage said plate to secure said medial gauge strip in an adjusted position. 115

4. A slug cutting machine comprising a bed, a gauge member adjustable thereon and having means whereby the same may be secured in adjusted position, said bed being provided with an upstanding lug adapted to cooperate with one end of said gauge member in indicating the position of a slug when the same is to be cut longitudinally, a blade adjacent said gauge member and having a lateral branch for use in making a short transverse cut, and a second blade co-acting with said first blade. 120

5. A slug cutting machine comprising a bed, a squared rectangular rod adjustably 125

connected thereto, and a gauge head having direct connection with said rod, and an adjustable gauge strip associated with said head.

5. 6. A machine of the character specified comprising a bed having cutting means, a block having an attaching rod secured to said bed, an arm slideable transversely of its axis and carried by the block, contact points carried by the arm and directed toward the work in advance of the block, and a vernier adjustment for the arm.

10 7. A machine of the character specified comprising a bed having cutting means, a block having an attaching rod secured to said bed, an arm slideable transversely of its axis and carried by the block, contact points carried by the arm and directed toward the work in advance of the block, and a vernier 20 adjustment for the arm, and means whereby the block may be secured in an adjusted position.

8. In a machine of the class described, the combination of a bed having a stationary 25 cutting blade transversely carried by said bed, a superposed lever carried blade, brackets at either side of the bed for supporting said lever and its operating means, said lever and brackets lying in planes parallel to 30 and outwardly offset from the plane of said blade, whereby to leave the transverse portion of the bed entirely unobstructed adjacent said stationary blade to admit of the accurate transverse adjustment of the work 35 to project from one side of the bed to the other.

9. In a machine of the class described, the combination of a bed having a stationary cutting blade transversely carried by said 40 bed, a superposed lever carried blade, brackets at either side of the bed for supporting said lever and its operating means, said lever and brackets lying in planes parallel to and outwardly offset from the plane of 45 said blades, whereby to leave the transverse portion of the bed entirely unobstructed adjacent said stationary blade to admit of the accurate transverse adjustment of the work to project from one side of the bed to the other, and gauge means associated with said 50 bed for guiding the work in its transverse adjustment across said bed.

10. In a machine of the class described, the combination of a bed having a stationary 55 cutting blade transversely carried by said bed, a superposed lever carried blade, brackets at either side of the bed for sup-

porting said lever and its operating means, said lever and brackets lying in planes parallel to and outwardly offset from the plane 60 of said blades, whereby to leave the transverse portion of the bed entirely unobstructed adjacent said stationary blade to admit of the accurate, transverse adjustment of the work to project from one side of the bed to the other, and gauge means associated with said bed for guiding the work in its transverse adjustment across said bed, said gauge means including a longitudinally adjustable strip carried by said bed.

70 11. In a machine of the class described, the combination of a bed having a stationary cutting blade transversely carried by said bed and having a laterally offset end, a superposed lever carried blade, brackets at either side of the bed for supporting said lever and its operating means, and said lever and brackets lying in planes parallel to and outwardly offset from the plane of the laterally offset end of said stationary blade, whereby 75 to leave the bed entirely unobstructed adjacent said stationary blade to admit of the accurate transverse adjustment of the work from one side of the bed to the other.

80 12. A machine of the character specified comprising a bed having cutting means, a block slideable toward the cutting means, an arm slideable transversely of its axis and carried by the block, the ends of the arm extending beyond the sides of the block, contact points carried by the arm beyond the sides of the block and directed toward the work in advance of the block, and means for adjusting the arm relatively of the block and in the direction of the work.

85 13. A machine for cutting slugs comprising a bed having a fixed knife, a movable knife cooperating with the fixed knife in cutting slugs, a medial rib having means to position the slugs when extended longitudinally or transversely, and one of said knives having a lateral offset cooperating with the other knife for cutting a rectangular segment from one edge of a slug in a single operation.

90 14. A machine for cutting slugs comprising a bed, a movable gage thereon for abutting one edge of a slug transversely of the bed, and cooperating cutting knives, having means associated therewith for cutting a rectangular segment from one edge of a slug in a single operation.

In testimony whereof I affix my signature.
JESSE D. LASSWELL.
